UNITED STATES PATENT OFFICE.

EMILE CORNELY AND ROBERT CORNELY, OF PARIS, FRANCE.

OVEREDGE SEWING-MACHINE.

SPECIFICATION forming part of Letters Patent No. 543,295, dated July 22, 1895.

Application filed January 21, 1895. Serial No. 53²,706. (No model.)

To all whom it may concern:

Be it known that we, EMILE CORNELY and ROBERT CORNELY, residents of Paris, France, have invented a new and useful Improvement 5 in Overedge Sewing-Machines, which is fully set forth in the following specification.

This invention has reference to machines for producing an edging or overseaming stitch by means of several threads, and resembles in many respects the machine described in our pending application, Serial No. 525,145, filed October 6, 1894.

The stitch-forming mechanism of our present mechanism is, like that of the said prior 15 application, adapted to be controlled by the operating-handle of the universal feed mechanism.

The seam, according to the present invention, is produced by the co-operation of a reciprocating eye-pointed needle, a helicoidal or corkscrew-shaped needle, and a shuttle. The seam is composed of three threads, (or two if desired,) one being fed from each of the above-mentioned parts. The operation 25 of the helicoidal needle is substantially the same as in our apparatus above referred to, forming at each complete movement a loop both on the top and bottom of the fabric. The reciprocating eye-pointed needle (in- 30 stead of carrying the loop from below up through the loop on the top of the fabric, as was the function of the hook-needle in our former application) loops a separate thread through the loops formed by the helicoidal needle, said thread lapping from one loop to the other on the upper side of the fabric, holding these loops together against the surface thereof. The shuttle feeds a thread 35 through the loops in the second thread carried to the under side of the fabric by the reciprocating eye-pointed needle.

The seam resulting from the operations above described consists of a series of parallel loops, both on the top and bottom of the 45 fabric, formed by a single thread held in position against the fabric by a lock-stitch seam produced from the two additional threads by the eye-pointed needle and the shuttle in a well-known manner.

50 In the accompanying drawings, forming parts of this specification, Figures 1 to 4, in-

clusive, are enlarged views in elevation partly in vertical section, illustrating the movements of the needles in forming a stitch. Fig. 5 is a plan view of a part of a seam, 55 such as produced when the shuttle mechanism shown in Fig. 11 is employed. Fig. 6 is an elevation, partly in section, of the parts beneath the bed-plate. Fig. 7 is an elevation at right angles to Fig. 6. Figs. 8, 8^a, and 8^b are details illustrating the operation of a reciprocating looper, which may be employed in place of the shuttle shown in Fig. 6. Figs. 9 and 10 are detail views. Fig. 11 is an enlarged detail view of the shuttle mechanism. 65 Figs. 12 and 13 represent a seam produced when a reciprocating looper, such as shown in Figs. 8, 8^a, and 8^b, is employed, and Fig. 14 shows the stitch-forming devices connected with the crank-handle of universal-feed 70 mechanism.

Referring to Figs. 1 to 4, inclusive, we will first describe the movement of the needles in forming the seam without reference to the particular mechanism for operating the same. 75

C represents the helicoidal needle; B', the reciprocating eye-pointed needle, and A the needle-plate. The needle C, which is carried by shaft D, has a thread-groove 16 along its outer circumference leading to the eye 3. 80 Shaft D reciprocates in line with its axis and also turns thereon, so that needle C has a corkscrew motion, as in the machine described in our former application. As illustrated in Fig. 1, the needle C is at the limit of its upward 85 movement, having passed through opening 2 in needle-plate A. The eye-pointed needle carrying thread i is, as shown, descending and its point is just about to enter opening 1 in plate A, having passed between the needle C and thread 4. From this position both needles descend, the needle C drawing a loop 4 around the needle B' (see Fig. 2) and the latter carrying thread i through said loop to the under side of the fabric. The needle B', 95 having descended to its lowest position, forms a loop upon rising, Fig. 3, which is seized by the hook 32 of the circular oscillating shuttle-case a', (see Fig. 11,) described hereinafter, which operates in the well-known manner and 100 which passes its thread o through the open needle-loop. During this operation the nee-

dle C winds its thread below the cloth around needle B', and when the latter rises farther its thread is drawn upward by the take-up, and at the same time the looper-needle C rises 5 and passes its thread upward, as represented in Fig. 4, where the stitch is finally completed, as represented in said figure. In this last position, the stitch being complete, it is ready to be slipped from the tongue 15 of needle- 10 plate A, which is formed by connecting openings 1 and 2 by a semicircular slot. (See Fig. 10.) The feed of the machine releases the stitch from the tongue, laying it on the fabric, against which it is tightly drawn by the 15 succeeding movements of the needles. From the position shown in Fig. 4 the needles move to that shown in Fig. 1, where the formation of a new stitch begins, as above described, these operations repeating themselves *ad infinitum* 20 and the result being a seam similar to that illustrated in Fig. 5.

Any shuttle device may be employed in conjunction with the eye-pointed needle B' when the shuttle-driver has an oscillating motion—such, for instance, as the Singer oscillating shuttle, (represented in Fig. 11,) where 25 a' represents the shuttle-case, which oscillates on its stud c' and which is provided with a suitable hook 32 to seize the loop of the eye-pointed needle B'.

33 represents the shuttle-driver, which is secured to the pinion b' and receives its oscillating motion by means of the toothed sector d', as hereinafter described.

35 Any suitable mechanism may be used to impart proper movements to the several needles and the shuttle. The mechanism illustrated in the drawings for operating the helicoidal needle C is similar to that shown in 40 Figs. 9 and 10 of our pending application.

Referring to the drawings, Q is the bed-plate of the machine, beneath which is a frame R, resting upon bracket P, in which shaft D, carrying the needle C, has bearings. Said 45 shaft D passes through a hollow worm-shaft U, to which it is adjustably secured by a thumb-nut u. Shaft U has a longitudinal groove h along one side thereof and engages an interiorly-threaded fixed nut O, secured in 50 frame R by a pin o'. A bevel-pinion M encircles shaft U below nut O, being supported in place by a plate N, secured to frame R. The pinion M is provided with an inwardly-projecting tooth g or feather, which engages 55 in groove h, causing shaft U to rotate with the pinion, but leaving it free to move longitudinally. The bevel-pinion is oscillated by a toothed sector L, meshing therewith, said sector being rocked on its pivot by a link K, 60 connected with a reciprocating sleeve H, to which motion is imparted from operating parts of the machine by pitman G. It will thus be seen that the oscillation of pinion M produces the necessary rotary and reciproca- 65 tory movements of needle C.

The machine herein described being adapt-

ed to be governed by the crank-handle of a universal feeding mechanism the frame R, with all its connections, must be so mounted as to rotate. To this end its upper end projects into an opening in bed-plate Q, beneath which it is encircled by a gear-wheel y, driven from the crank-handle through gears x w v, shaft u, and gears 8, 7, and 6, as shown in Fig. 14.

75 In our present machine, wherein a shuttle-case a' is employed, additional mechanism is required to operate the same. This mechanism, which is mounted on and carried by the frame R, consists of a toothed sector d', pivoted to the frame by a screw g' and oscillated by a link h', connected with the reciprocating sleeve H. The teeth of sector d' engage a pinion b', carrying shuttle a' and bearing on a shaft c', screwed into the frame R. The 80 shuttle a' and its accessory parts operates in a well-known manner to pass the thread o through the needle-loop in thread i, which requires no explanation. It is evident that the threaded needle can also work in conjunction with a reciprocating looper z, Figs. 8, 8^a, and 8^b, instead of the shuttle a', to produce the seam illustrated in Figs. 12 and 13. The looper z is secured to the oscillating pinion b' and catches the loop of needle B' when 85 turning to the left, Fig. 8, spreading said loop on its further motion while the needle is rising, so that on the return motion of the looper z, and as the needle B' descends, it will stitch into the spread-loop, as represented at Figs. 90 8^a and 8^b, thus producing the seam referred to, comprising loops 4 and chain-strokes 5. The production of the overseaming stitch will be the same as represented at Figs. 1, 2, 3, and 4, only with the difference that a chain-stitch 95 will be produced on the lower side of the material instead of the shuttle-stitch represented in Fig. 5.

100 It will of course be understood that our invention is not limited to the precise mechanism herein described, as other embodiments thereof in a practical apparatus may be completed without departing from the principle thereof.

105 What we claim is—

110 1. In a sewing machine, the combination 115 with the reciprocating eye-pointed straight needle and its complemental loop-taker, and means for operating the same to form a seam, of the helicoidal eye-pointed needle and means for giving the latter longitudinal reciprocating movements and axial oscillating movements, whereby a series of loops are formed on both sides of the fabric and said loops secured to the fabric by said seam, as 120 set forth.

125 2. In a sewing machine, the combination, 130 with the reciprocating eye-pointed straight needle and a complemental lock-stitch loop-taker, and means for operating the same to form a seam, of the helicoidal eye-pointed needle and means for giving the latter long-

tudinally reciprocating movements and axial oscillating movements, whereby a series of loops are formed on both sides of the fabric and said loops secured to the fabric by said seam, as set forth.

3. In a sewing machine, the combination with a universal feed-mechanism of a reciprocating eye-pointed straight needle and its complemental loop-taker, means for operating the same to form a seam, a helicoidal eye-pointed needle, means for giving the latter longitudinally reciprocating movements and axial oscillating movements whereby a series of loops are formed on both sides of the fabric and secured to the fabric by said seam, a

rotatable frame carrying the helicoidal needle, its complemental loop-taker and their operating mechanism, and connections between said frame and the controlling handle of the feed-mechanism whereby the frame is operated by the latter, substantially as described. ²⁰

In testimony whereof we have signed this specification in the presence of two subscribing witnesses.
